ARTHUR C. BADGER, OF NEWTON, MASSACHUSETTS, ASSIGNOR TO E. B. BADGER & SONS COMPANY, OF BOSTON, MASSACHUSETTS, A CORPORATION OF MASSACHUSETTS.

HOLDER FOR WOOD BEING DISTILLED.

1,338,667.

Specification of Letters Patent.

Patented May 4, 1920.

Application filed July 26, 1916. Serial No. 111,534.

To all whom it may concern:

Be it known that I, ARTHUR C. BADGER, a citizen of the United States, residing at Newton, in the county of Middlesex and 5 State of Massachusetts, have invented new and useful Improvements in Holders for Wood Being Distilled, of which the following is a specification.

The present invention relates to the art 10 and practice of distilling wood to obtain wood alcohol and other products, and its ultimate object is to provide an improved holder for the wood being distilled, by the use of which the distillation may be carried on more rapidly and efficiently, and a greater proportion of the volatile constituents of the wood may be obtained.

In the practice of wood distillation as heretofore commercially carried on, the 20 logs or sticks of wood are placed upon cars and the latter are wheeled into retorts, which are closed to exclude air and are heated to the temperature of destructive distillation of wood; the retorts having 25 proper outlets for withdrawal of the gaseous and liquid products of such distillation. This process, as heretofore practised, is inefficient for two main reasons, first that a long time is required for the complete 30 distillation of the wood, and second that a large proportion of the products desired to be obtained, particularly wood alcohol, acetone, and similar compounds, by reason of the long period of heating to which they 35 are subjected, are broken down into worthless compounds, namely carbon dioxide and water vapor, and practically lost. I have discovered that the cause of the waste and inefficiency of the old process is the mode 40 of stacking the wood on the cars, the entire charge carried by each car being piled in a single stack substantially as long as the car itself, whereby the pieces at the ends and at the top of the stack so cover 45 the interior pieces that penetration of heat to the interior of the stack and escape of vapors therefrom is much impeded. Even though the pieces of wood be rough logs or untrimmed split sections of logs, yet the 50 spaces between the logs or sections are so small in proportion to the masses of the pieces themselves that there is not sufficient space for immediate escape of the vapors liberated by distillation, and escape of a 55 part of the vapors is entirely prevented by

filling of the spaces between the pieces of wood by tar, water, and other liquids exuding from the wood. The length of time required for completely reducing to charcoal the ordinary charge of wood is usually 60 about 48 hours, and the percentage of waste of the alcohol content of the wood due to destructive distillation of the entrapped vapors of alcohol, acetone, etc., is ordinarily 65 great.

The purpose of my invention is to shorten the time required for the distillation of wood on a commercial scale, while using the method according to which unit holders with their charges of wood are bodily 70 placed in and removed from the retorts, and to reduce the waste from destructive distillation of alcoholic vapors to the minimum. I have accomplished this object by providing a means or apparatus for holding the charge of wood in the retort constructed to provide unobstructed vertical spaces between relatively small subdivisions of the entire charge and access from within such subdivisions to said spaces, such spaces 75 being near enough together and sufficiently wide to permit immediate escape of the vapors discharged from the wood and rapid penetration of heat to all parts of the charge. While the principles of the invention may be applied in many diverse forms, I prefer to apply such principles to a carrier or container having supporting wheels similar to those of the ordinary flat car heretofore used, and to provide on such 80 carrier spacing members arranged to provide pockets for containing the subdivisions of the entire charge or load, with spaces open through the bottom of the car between such subdivisions; and also to line 85 the spaces which receive the charge with walls having a sufficiently open character to permit free passage of vapor and liquids, while retaining the charcoal which remains 90 and disintegrates into small pieces in the 95 process.

In the drawings, Figure 1 is a cross section of a retort showing in end elevation a container or carrier embodying my invention.

Fig. 2 is a plan view of the carrier or container.

Fig. 3 is a side elevation of the same.

In the following specification I will call the carrier or container for the charge to 110

be distilled by the common descriptive term "car", on account of the fact that in its preferred form such carrier is provided with wheels in the manner of a car; but it is to be understood that in adopting this term of description I have not intended to imply any limitation in the scope of the invention to a carrier or container equipped with wheels, or otherwise limited except as expressed by the terms of the following claims. 10 represents a retort. As shown in cross section in Fig. 1 it has a floor, side walls, and a roof completely inclosing the space in which the charge is contained, and its floor supports rails 11 on which the wheels of the car may run. I have not attempted to show the end walls or the doors, or other means for closing and sealing the opening through which the car is passed, 20 or the outlet for withdrawing vapors and liquid products of distillation, for these elements do not form a part of my invention and are well understood in the art.

The car may be of any construction as to 25 its body and is shown as having longitudinal sills 12 at the sides, and cross pieces 13. The traction wheels 14 are mounted in bearing brackets 15 or connected in any other desired way.

30 At intervals spaced longitudinally of the car are uprights or posts 16 which may be, and are here shown as being made of angle stock, but may be of any other construction which provides the desired distance between 35 their opposite faces or edges. Enough posts are provided in transverse rows on the car to define spaces or pockets 17 into which logs or sticks of wood 18 may be placed as indicated at the left hand end of the car 40 in Figs. 2 and 3. The sides and bottoms of the pockets 17 are lined with woven wire fabric 19, or any other porous fabric, for example, perforated sheet metal, the purpose of which is to retain the separated and 45 broken lumps of charcoal remaining at the end of the distilling operation. The adjacent pockets 17 are separated from one another by the thickness of the posts 16. The latter may be considered, therefore, to divide 50 the entire charge on the car into subdivisions of comparatively short extent. Between posts in each row are spaces 20, shown in Fig. 2, which pass from the bottom of the car up to the top of the charge and are open 55 at both ends, since the car bottom is of open construction, as previously explained. It may be noted that the posts are mounted on longitudinal stringers 21 parallel to the sills of the car bottom and that the spaces between these stringers are open.

60 It will be apparent that the passages 20 permit free and undisturbed passage upward of heated gases between the subdivisions 18 of the charge, and freely admit 65 vapors liberated from the wood passing

through the perforated walls or linings 19. Thus by reason of the subdivision of the charge, heat may pass to all parts of the charge in the most rapid possible manner, and the liberated vapors may pass away 70 from the charge immediately upon liberation and be withdrawn from the retort before they have had time to be decomposed by prolonged heating.

I have found that satisfactory results may 75 be obtained when the width of the pockets 17 is approximately 12 inches, and of the passages between the pockets approximately 3 inches, as a vertical stack of wood of approximately 12 inches width is sufficiently 80 narrow and open to permit immediate release of all volatile products of distillation, and passages of 3 inches width are sufficiently wide to conduct away all such volatile products as fast as they are delivered. 85 The figures given, however, are intended to be merely illustrative and not to limit this feature of the invention to any specific dimensions or proportions. The principle which I wish to protect is that rising 90 passages through which heated vapors may travel upwardly are provided at such intervals in the charge and have such size that the distilling heat may penetrate rapidly to all parts of the charge and the vapors delivered may escape immediately upon their 95 liberation and may be immediately withdrawn from the retort.

The practical results of my invention as above described have been to reduce the time 100 required for distillation of a complete charge, by about twenty per cent, more or less, and to prevent destructive distillation 105 of the valuable vaporous and gaseous constituents of the wood, notably wood alcohol and acetone.

With the use of this apparatus I carry out a new method of stacking wood for distillation, which broadly stated, consists in arranging the pieces of wood in piles or stacks 110 of relatively slight width as compared to the whole charge, and leaving open spaces between the stacks. Such method I also claim as a part of my invention, and I so claim the method without limitation to the specific 115 means shown and hereinbefore described with the help of which the method is carried out.

What I claim and desire to secure by Letters Patent is:

1. A holder for wood undergoing destructive distillation, comprising lateral sills and intermediate longitudinal stringers, forming an open frame, posts erected on said sills and stringers in a series of lines transverse to the stringers, and open work material covering said bottom frame between the lines of posts and rising on each side of each of said lines, the spaces thus enclosed by said open work material being 130

compartments for receiving wood, and the spaces between the posts of each line being entirely open and unobstructed from top to bottom.

5. 2. A holder for wood undergoing destructive distillation comprising a series of compartments having open work walls in which wood may be stacked, and spaces between said compartments extending up and down 10 and open throughout and at the top and bottom for free passage of gases and vapors, said compartments having perforated bottoms adapted to support the disintegrated residue of the distilling process, while at 15 the same time permitting passage of vapors and gases.

3. A holder for wood to be distilled comprising a self-contained structural unit adapted to be placed in and removed from 20 a distilling retort, having separate compartments for the wood to be distilled and spaces between said compartments open above and below and having access to said compart-

ments, whereby to permit free escape at the same time from different parts of the charge 25 of wood carried by said holder, of vapors produced by distillation.

4. A holder for wood to be distilled comprising a unit structure adapted to be placed in and removed from the retort and having 30 a plurality of separate compartments with intervening open spaces, said compartments being adapted to receive sections of the charge of wood carried by the holder and having open work sides and bottoms to 35 permit free passage to and from them of gas and vapors, the meshes of such open work being relatively small whereby to retain fragments of charcoal resulting from distillation, the intermediate spaces being 40 open through the bottom of the holder to permit free upward passage of heated gases and vapors.

In testimony whereof I have affixed my signature.

ARTHUR C. BADGER.
